UNITED STATES PATENT OFFICE.

NICK YACK, OF POLONIA, WISCONSIN.

RUNNER ATTACHMENT FOR WHEELBARROWS.

1,012,643.

Specification of Letters Patent. Patented Dec. 19, 1911.

Application filed April 17, 1911. Serial No. 621,626.

To all whom it may concern:

Be it known that I, NICK YACK, a citizen of the United States, residing at Polonia, in the county of Portage and State of Wisconsin, have invented certain new and useful Improvements in Runner Attachments for Wheelbarrows; and I do declare the following to be a full, clear, and exact description of the invention, such as will enable others skilled in the art to which it appertains to make and use the same.

This invention relates to improvements in sled runner attachments for wheel barrows.

One object of the invention is to provide a runner attachment for wheel barrows adapted to be applied thereto in the position usually occupied by the wheel and which is interchangeable with the wheel.

Another object is to provide a runner attachment of this character having an improved construction and arrangement of braces whereby the runner is securely held in position to properly engage the surface on which the same rests irrespective of the angle or position in which the body of the wheel barrow is held.

With these and other objects in view, the invention consists of certain novel features of construction, combination and arrangement of parts as will be more fully described and particularly pointed out in the appended claim.

In the accompanying drawings: Figure 1 is a plan view of a wheel barrow showing my improved runner attachment applied thereto; Fig. 2 is a side view of the same with the outer end of the near handle bar broken away and the shaft in section. Fig. 3 is a vertical cross sectional view through the outer ends of the handle bars and the runner on the line with the runner attaching shaft.

Referring more particularly to the drawings, 1 denotes the body of the wheel barrow which may be of any desired form or construction and which is provided with the usual handle bars 2 and supporting legs 3.

In the outer ends of the handle bars 2 is arranged a transversely disposed shaft 4 the outer ends of which project a slight distance beyond the outer sides of the handle bars and are threaded to receive fastening nuts 5 whereby the shaft is removably secured to the bars. To the shaft 4 is pivotally con-

nected my improved runner 6 having an upwardly curved forward end and having secured to its edge a metal shoe 7. The shoe extends entirely around the edge of the runner and has its upper portion bent upwardly to form a bearing eye 8 which is engaged with the shaft 4 and thus pivotally secures the runner to the shaft.

To the opposite sides of the runner are secured right angular bracing bars 9, said bars being pivotally engaged at their inner upper corners with the shaft 4 as shown. The vertical arms 10 of the braces are bent inwardly from the inner upper corners of the braces toward the sides of the runner and are then bent downwardly to form runner engaging lugs 11 through which and through the runner is inserted a pivot bolt or rivet 12 whereby the braces are secured to the rear horizontal portion of the runner. The upper forwardly projecting members 13 of the braces are also bent inwardly from the inner corners of the braces toward the front end of the runner and are thence bent forwardly to form runner engaging lugs 14 through which and through the upper end 80 of the runner is inserted a bolt or rivet 15 whereby this end of the runner is securely fastened to the braces. By forming the braces 9 as herein shown and described a simple, strong and durable construction is 85 provided whereby the runner is effectually braced both laterally and longitudinally and thereby held against strain occasioned by turning the wheel barrow in different directions.

From the foregoing description taken in connection with the accompanying drawings, the construction and operation of the invention will be readily understood without requiring a more extended explanation.

Various changes in the form, proportion and the minor details of construction may be resorted to without departing from the principle or sacrificing any of the advantages of the invention as defined in the appended claim.

Having thus described my invention, what I claim is:

A runner for a wheel barrow comprising a main body, a shoe around said main body having its upper portion bent to form a bearing eye for the wheel barrow axle, and a brace bar on each side of the shoe bent

edgewise at substantially a right angle forming a horizontal and a vertical arm, and provided at the angle with a bearing opening for the axle, both the vertical and horizontal arms being bent inwardly at an inclination and secured at their lower and forward ends respectively to the body of the runner.

In testimony whereof I have hereunto set my hand in presence of two subscribing witnesses.

N. YACK.
